Primary Examiner — Catheri Oliver-Garcia(74) *Attorney, Agent, or Firm* — Thorpe North & Western, LLP(57) **CLAIM**

The ornamental design for a belt mount rifle sling holder, as shown and described.

DESCRIPTION

FIG. 1 is a front perspective view of the belt mount rifle sling holder in accordance with my invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The surface indicia of parallel lines also form no part of the claimed design and are merely contour shading.
